[57] **CLAIM**

The ornamental design for a back plate for a light fixture, as shown and described.

DESCRIPTION

FIG. 1 is a front view of a back plate for a light fixture; FIG. 2 is a right side view of the back plate for the light fixture; with the left side view being an identical mirror image;

FIG. 3 is a back view of the back plate;

FIG. 4 is a top plan view of the back plate; and, FIG. 5 is a bottom plan view of the back plate.

The stippling shown on the drawings is for shading purposes and does not form a part of the invention.
